(57) **CLAIM**

The ornamental design for a dual monitor/screen for a laptop computer with support for the second monitor, as shown and described.

DESCRIPTION

FIG. 1 is a perspective view of a dual monitor/screen for a laptop computer with support for the second monitor showing my new design;

FIG. 2 is another perspective view thereof with the second monitor being shown inserted into the first;

FIG. 3 another perspective view thereof with the second monitor being shown angled off from the first;

FIG. 4 is a top view thereof;

FIG. 5 is a bottom view thereof;

FIG. 6 is a side view thereof;

FIG. 7 is an opposite side view thereof;

FIG. 8 is a back view thereof; and,

FIG. 9 is a front view thereof.
